[57] **CLAIM**

The ornamental design for a fluid delivery pump for intravenous solutions, as shown and described.

DESCRIPTION

FIG. 1 is a perspective view of a fluid delivery pump for intravenous solutions, showing our new design with a syringe installed and shown in broken lines for illustrative purposes only and forming no part of the claimed design;

FIG. 2 is a top plan view thereof, with the syringe removed;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.

FIG. 1

FIG. 2

FIG. 3

FIG. 4

FIG. 5

FIG. 6

FIG. 7
